2,029,601

CONVERSION OF HYDROCARBON OILS

George D. White, Port Arthur, Tex., assignor to
 The Texas Company, New York, N. Y., a corporation of Delaware

Application April 30, 1934, Serial No. 723,065

2 Claims. (Cl. 196—48)

This invention relates to the conversion of hydrocarbon oils and has reference to a method of treating the oil in which selected fractions having different boiling ranges are first separated and the separated fractions subjected to different heat treatments under optimum conditions to produce the desired end products.

One of the principal objects of the invention is to improve the method of heat treating the hydrocarbons so as to reduce coke formation in the heating unit without lowering the efficiency of the process or the quality of the motor fuel produced.

In accordance with my invention, a selected clean cycle stock, preferably withdrawn from a secondary fractionating zone, is heat treated under relatively drastic temperature conditions, such as for example vapor phase cracking conditions, and thereafter immediately commingled with relatively cooler and heavier hydrocarbon oil stock, preferably comprising the bottoms of a primary fractionating and distilling zone, into which fresh oil may be charged. The commingled hydrocarbons are then passed through an additional heating coil in which they are subjected to less drastic temperature conditions, and are then passed to a suitable chamber for separating the reaction products into vapors and unvaporized residual material, and in which additional cracking may take place.

Other and more detailed objects and advantages of the invention will appear in the description hereinafter.

With the above objects and advantages in view, the invention will be best understood by referring to the accompanying drawing which is a schematic illustration of an apparatus which may be employed for carrying the invention into effect.

Referring to the drawing, the apparatus in general comprises a furnace 10, a separating or cracking chamber 11, a primary fractionating and distilling tower 12, and a secondary fractionating tower 13, together with the necessary connecting pipe lines provided with suitable pumps and valves for causing the hydrocarbons to flow in the manner hereinafter described. It is to be understood that in addition to that shown, the apparatus in its entirety will include other conventional equipment and appurtenances normally making up a complete conversion unit such as temperature and pressure indicating and control devices for maintaining and controlling the temperature and pressure conditions in the unit. It is also to be understood that the ap-

paratus shown may be employed in conjunction with other apparatus for carrying out further separation and purification of the end products produced in the apparatus illustrated.

In carrying out my invention a clean condensate stock formed by fractionating vapors in the secondary fractionating tower 13 is withdrawn from the latter tower through line 14 provided with a pump 15 which forces the withdrawn condensate through the heating coil 16 located adjacent the side walls in the radiant heat section of the furnace 10. The condensate passing through the wall tubes is subjected to cracking temperature conditions for carrying out the conversion treatment. For example, the condensate during its passage through the tubes may be heated to temperatures ranging from 900 or 950 to 1050° F. The oil thus heated is withdrawn from the radiant heat section of the furnace, preferably before final conversion has taken place, and the oil thus heated is passed through the line 17 and commingled immediately in line 18 with a cooler hydrocarbon stream withdrawn from the bottom of the primary fractionating tower 12 through line 19. The combined stream is then passed through line 18 into a heating coil 20 wherein further conversion of the clean lower boiling condensate and an initial conversion or viscosity breaking of the heavier stock from the bottom of the primary fractionating tower 12 is effected. The reaction products from the heating coil 20 are discharged through transfer line 21 into the chamber 11 wherein additional cracking may be accomplished. As illustrated, a portion of the heated condensate from the radiant zone of the furnace may be by-passed through line 22 around the heating coil 20 and introduced into the transfer line 21 leading from the coil 20 to the chamber 11.

The oil in the chamber 11 is separated into vapors and unvaporized constituents. The vapors are withdrawn from the chamber 11 through the line 23 and introduced into the primary fractionating tower 12 which may be provided with suitable cooling and fractionating elements. The unvaporized residue is withdrawn from the chamber 11 through line 24 and discharged from the system, being passed to suitable storage receptacles or subjected to further treating as desired.

The vapors passing through the tower 12 are subjected to fractionation to condense the higher boiling constituents therefrom. The uncondensed vapors from tower 12 are then passed through the line 25 to the secondary fractionat-

ing tower 13 where they are subjected to final fractionation. The vapors from the top of the secondary fractionating tower 13 which contain the gasoline constituents are withdrawn through line 26 and passed to a condenser 27 for condensing the gasoline constituents, after which they are passed to a gas separator 28 for separating the gases from the gasoline distillate. Gasoline distillate from the separator 28 is then withdrawn through line 29 and passed to suitable storage receptacles or subjected to further treatment as desired. As shown, a part of the gasoline may be returned to the fractionating tower 13 through line 31 to serve as a cooling and refluxing agent.

As illustrated, fresh charging stock, with or without preheating, may be introduced either into the separating chamber 11 or the primary fractionating tower 12, or into both of these chambers. For example the fresh charging stock, which may be a crude, reduced crude, or heavy ("dirty") gas oil, may be introduced into the system through line 32 provided with a pump 33. The fresh charge may be preheated by passing in series through a heat exchange coil 34 located in the top of the secondary fractionating tower 13, thence by means of line 35, through heating coil 36 located in the economizer section of the furnace, and then discharged into either or both chambers 11 and 12. A portion or all of the fresh charge may by-pass either or both the heating coils 34 and 36 through lines 37 and 38 respectively, and introduced into chambers 11 and 12. Under normal operation I prefer to introduce a major portion of the fresh charging stock into the primary fractionating and distilling tower 12, so that the unvaporized constituents of the charge will be combined with condensate formed in the chamber and will be subjected to a mild conversion treatment in the nature of a viscosity breaking operation in coil 20, as hereinbefore described. The fresh charge introduced into tower 12 will be further heated by the more highly heated vapor products undergoing fractionation and will be stripped of whatever lighter constituents, such as gasoline, kerosene, or light gas oil which may be present in the original charge. As an alternative a portion or all of the fresh charge may be introduced into chamber 11 in which case the charge will be distilled and subjected to cracking in chamber 11 to the final residual products by the heat of the more highly heated products from the heating coils 16 and 20.

For simplicity only a single separating or cracking chamber 11 and a single primary fractionating and distilling tower 12 have been illustrated. It will be understood, however, that any desired number of these chambers connected either in series or parallel may be employed if desired.

The following specific example of operating conditions to be employed may be helpful in attaining a clear understanding of my invention. It is understood, however, that the invention is not limited to the specific example given as the desired operating conditions will vary, depending upon external factors, such as the character of the charging stock and desired end point of the gasoline produced. However, with the information here contained the desired operating conditions in each circumstance will be evident to those familiar with this art.

As before mentioned the clean condensate stock from the bottom of the secondary fractionating tower 13 may be brought to a temperature ranging from about 900 or 950 to 1050°

F. during its passage through the heating coil 16. The temperature and time of treatment may be such as to cause from about fifteen or twenty to about thirty percent (or even higher) conversion of the stock during its passage through the coil 16.

The heavier cycle stock withdrawn from the bottom of the primary fractionating tower 12 before merging with the hot products from coil 16 may be at a temperature ranging from 650 to 750° F. and the combined stream after merging, but before passing through coil 20, may be at a temperature ranging from about 750 to about 850° F. Sufficient heat may be supplied to the combined stream during its passage through the heating coil 20 to raise the temperature of the oil to a temperature of from about 800 to about 900° F., or higher, or only sufficient heat added to supply the normal heat losses resulting from endothermic reactions of the oil within the coil without any substantial increase in temperature of the oil.

The fresh or raw oil introduced into the system, from line 32, may be preheated to any desired degree, for example up to from 400 to 600° F. However, it may be heated to or subjected to a substantial cracking temperature, say 750 to 875° F., during its flow through the coil 36. In this event it is preferable to discharge the oil from the coil 36 into the distilling and cracking chamber 11 wherein it undergoes further conversion in admixture with the hot products from coils 16 and 20.

The pressure conditions may be maintained substantially uniform throughout the whole apparatus except for normal friction losses resulting from the passage of the products through the system, or if desired, pressure in the furnace coils 16 and 20 may be maintained higher than that in the remaining portion of the apparatus by providing a reducing valve in the line 21. The pressure conditions may vary over the normal range of pressure conditions employed in the treatment of hydrocarbon oils such as for example between 100 and 1000 lbs. per square inch. The invention, however, is particularly adaptable to relatively low pressure operations such as for example from 100 to 400 lbs. per square inch.

While the preferred embodiment has been described for purposes of illustration, it is to be understood that the invention embraces such other modifications or variations as come within the scope and spirit thereof and that the invention is not to be limited except as necessary to distinguish from prior art.

I claim:

1. In a process for converting higher boiling hydrocarbons into lower boiling hydrocarbons suitable for motor fuel, wherein cracked residual products are withdrawn from the system without being recirculated through a heating coil; the improvement which comprises passing a combined stream of oil of the character hereinafter specified through a heating coil maintained at a cracking temperature, maintaining the oil in said coil for a time sufficient to effect conversion of higher boiling hydrocarbons into lower boiling hydrocarbons, discharging the converted products from said coil into an enlarged chamber wherein separation of the vapors and unvaporized residual products is effected, maintaining the oil in said enlarged chamber at an active cracking temperature to cause further cracking thereof, withdrawing all of the residual products from the chamber and discharging them from the sys-

tem, separating the vapors by fractionation into a vapor fraction, a higher boiling condensate fraction and a lower boiling condensate fraction, separately condensing the vapor fraction to produce the desired distillate product, heating the lower boiling condensate fraction in a separate heating coil to a cracking temperature materially higher than that for said first mentioned heating coil to effect substantial conversion of said lower boiling fraction, thereafter immediately combining a portion of said highly heated lower boiling fraction with said higher boiling fraction, passing the combined stream to said first mentioned heating coil, and passing the remainder of said highly heated lower boiling fraction directly to said enlarged chamber to aid in maintaining a cracking temperature therein.

2. In a process for converting higher boiling hydrocarbons into lower boiling hydrocarbons suitable for motor fuel, wherein cracked residual products are withdrawn from the system without being recirculated through a heating coil; the improvement which comprises passing a combined stream of hydrocarbons of the character hereinabove specified through a heating coil, subjecting the hydrocarbons during their passage through the coil to a cracking temperature for a period sufficient to effect conversion of higher boiling hydrocarbons into lower boiling hydrocarbons, introducing the resulting products from said heating coil into an enlarged chamber wherein separation of vapors and unvaporized residual prod-

ucts is effected, maintaining the oil in said enlarged chamber at an active cracking temperature to cause further cracking thereof, subjecting the vapors from said enlarged chamber to progressive fractionation in primary and secondary fractionating zones to separate said vapors into a vapor fraction, a lower boiling condensate fraction and a higher boiling condensate fraction, introducing fresh charging stock into said primary fractionating zone wherein unvaporized constituents of the charging stock is admixed with said higher boiling condensate fraction, separately condensing the light vapor fraction to produce the desired distillate product, separately heating said lower boiling condensate fraction to a temperature materially higher than the final temperature of the hydrocarbons in said first named heating coil and for a period of time sufficient to effect a substantial conversion of the lower boiling condensate fraction into hydrocarbons suitable for motor fuel, thereafter immediately combining a portion of the converted products of said lower boiling condensate fraction with the mixture of unvaporized constituents of the fresh oil and the higher boiling condensate fraction withdrawn from said primary fractionating zone, passing the combined stream to the first mentioned heating coil, and passing the remainder of said highly heated lower boiling fraction directly into said enlarged chamber to aid in maintaining a cracking temperature therein.
